(57) **CLAIM**

The ornamental design for a vehicle bonnet vent, as shown and described.

DESCRIPTION

FIG. 1 is a front left top perspective view of a vehicle bonnet vent according to the present invention.

FIG. 2 is a front left perspective view of the bonnet vent shown in FIG. 1.

FIG. 3 is a rear right top perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another top view of the bonnet vent shown in FIGS. 1-10, but mounted on a vehicle and with the rest of the vehicle shown in broken lines. The vehicle shown in broken lines is for environmental subject matter only and forms no part of the claimed design.

A second embodiment for a vehicle bonnet vent designed to mount on the opposite side of the vehicle is a mirror image of FIGS. 1-11.
